UNITED STATES PATENT OFFICE.

CHARLES WORKHEISER, OF SPRINGFIELD, MASSACHUSETTS, ASSIGNOR TO
THE NEWELL BROTHERS MANUFACTURING COMPANY, OF SAME PLACE.

MACHINE FOR CUTTING OUT PEARL-BUTTON BLANKS.

SPECIFICATION forming part of Letters Patent No. 508,795, dated November 14, 1893.

Application filed June 5, 1893. Serial No. 476,582. (No model.)

To all whom it may concern:

Be it known that I, CHARLES WORKHEISER, a citizen of the United States, residing at Springfield, in the county of Hampden and 5 State of Massachusetts, have invented new and useful Improvements in Machines for Cutting Out Pearl-Button Blanks, of which the following is a specification.

This invention relates to improvements in machines for cutting out from the shell pearl disks or circular blanks from which the buttons are afterward turned. Heretofore in machines for this purpose, so far as known to me, in which tubular, end-toothed, cutters 10 have been employed, the blanks have been, after being cut from the shell, left just within the working end of the cutter-tube, and they have, before the cutting-out of the next blank, been expelled forwardly by a suitable plunger working within the tubular cutter; the forcible ejection of the blank forwardly from within the teeth has often resulted in the chipping off of edge portions of the blanks to the injury of the latter, and the principal object 15 of this invention is to devise a cutter for the indicated purpose by the use of which the forward ejection of the blanks, intermediate of the cutting operations, is unnecessary and by the use of which the chipping off of edge- 20 wise portions of the blanks is avoided.

Another object is to make provision for the wear of the tubular cutter, so that practically the entire length of the cutter tube may be utilized by regrinding. And to these ends 25 the invention consists in the construction and combination of parts, all substantially as will hereinafter fully appear and be set forth in the claims.

In the drawings accompanying,—Figure 1 30 is a sectional elevation of the blank cutting machine. Fig. 2 is a side view of the cutter-tube and its holder. Figs. 3 and 4 are perspective views of sections, one or both of which may form the seat with which the cutter-tube 35 has, by its rear end, an engagement. Fig. 5 is a perspective view of the removable, steady- 40 ing collar which surrounds an intermediate part of the cutter-tube. Fig. 6 is a perspective view of the cutter-tube, while Fig. 7 is a 45 perspective view of a blank as cut out by this machine.

Similar letters of reference indicate corresponding parts in all of the views.

In the drawings, A represents the head-stock mounted for rotation and carrying the 55 hollow cylindrical or tubular holder, B, for the tubular cutter, C, the ratchet-like cutting teeth, *a*, of which are arranged upon the forward end thereof. The rear end of the holder is solid and has the screw tang, *b*, which enters a screw-tapped socket therefor in the head-stock. The tubular holder, B, has there- 60 within a seat upon which rests,—and with which engages to turn therewith,—the rear end of the cutter tube. The seat may be con- 65 stituted by the forward end of the annular section, *d*, or by the forward end of another annular section, *d*². The engagement, which the rear end of the cutter has with the seat therefor, is through the interengaging teeth, 70 *f*, of the rear end of the cutter and the teeth, *f*², of the seat.

In order that the rear end of the cutter-tube (the walls of which tube are comparatively thin) may have sufficient strength to withstand the force for rotation imparted through the toothed seat of the holder to the rear teeth of the tube, as well as the better to withstand the impact endwise while the cutter-tube is working, the latter is externally en- 75 larged as seen at *e*. The section, *d*, is re- 80 tained within the holder, B, to rotate as one therewith by the set screw, *c*, and has, at one side, the aperture, *h*,—while, next thereto, the holder has the aperture, *i*. The opening with- 85 in the annular seat forming section or sections, *d*, *d*², is of somewhat greater diameter than the passage through the cutter-tube, as also are the sidewise apertures, *h*, *i*, to insure the free discharge of the blanks. 9c

The cutter-tube is supported centrally at the forward end of the holder by the collar, *j*, which sets within the deep seat or rabbet, *k*, in the forward end of the holder, and is retained by the set screw, *j*². 95

The cutter-tube may be first applied in the holder with its rear toothed end against the forward end of the seat section, *d*, it being assumed to be then of sufficient length to pro- 100 trude suitably forward beyond the end of the holder;—but after several regrindings of the cutter teeth whereby the tube becomes

measurably shortened, one or more of the extra toothed seat sections, d^2 , may be inserted between the rear end of the cutter-tube and the sidewise recessed section, d .

5. The pearl stock is presented in any suitable or well known manner to the cutting end of the tube, C, and the blanks, as the work proceeds, are forced rearwardly through the tube and drop out at the discharge opening therefor through the holder, as manifest.

Having thus described my invention, what I claim, and desire to secure by Letters Patent, is—

1. In a machine for cutting out blanks for pearl buttons, the combination with the rotatably mounted tubular holder with an annular toothed seat at its rear, and the sidewise discharge opening adjacent thereto, of the tube having the cutter-teeth at its forward end, and having its rear end provided with teeth to engage the toothed seat within the holder, substantially as described.

2. In a machine for cutting out blanks for pearl buttons, the combination with the rotatably mounted tubular holder with a discharge opening at its rear, and having annular sections therein the rearmost one of which is recessed sidewise, and has teeth at its forward end and is detachably secured in the holder, one or more removable annular sections with toothed rear and forward ends, and the tube having the cutter-teeth at its forward

end and having teeth at its rear end, substantially as described.

3. In a machine for cutting out blanks from pearl, the combination with a tubular rotatably mounted holder having an annular seat therewith which is formed by two or more annular sections, one or more of which are removable, and the device having a discharge opening for the blanks, the cutter tube having its rear portion within the tubular holder and resting against the said section formed seat and means for preventing the rotation of the cutter-tube relative to the holder, substantially as described.

4. In a machine for cutting out blanks from pearl, the combination with the rotatable head-stock, the tubular holder, B, secured thereto, and having the sidewise opening, i , and the seat or annular rabbet within its forward end, of the annular section, d , secured within the holder, and having in its forward end, teeth, and the sidewise recess, h , the annular section, d^2 , toothed at front and rear, the tube with the cutter-teeth at its forward end and having teeth at its rear end engaging the said toothed section, and a centering collar, j , set in the said rabbet and surrounding the cutter-tube, substantially as described.

CHARLES WORKHEISER.
